INFANT'S GARMENT

Joseph Astrove, New York, N. Y., assignor to
Tidy Products Corporation, New York, N. Y.

Application March 3, 1938, Serial No. 193,617

1 Claim. (Cl. 2—114)

This invention relates to an infant's garment; more particularly to a combination sleeping garment, blanket and robe.

It is an object of my invention to provide an infant's garment in which a protective covering is provided, allowing for freedom of movement during the time the infant is lying in a crib or carriage, serving in the nature of a garment and blanket, yet including features which will permit accessibility to the infant for purposes of changing its undergarments.

It is further contemplated by my invention to provide an infant's garment in the nature of a robe, including parts thereof which fully cover the infant's body and including therewith features which permit accessibility to the infant's body to facilitate redressing the infant, as to its undergarments. It is further contemplated by my invention to provide a combined infant's garment and blanket which guards against the infant becoming uncovered or exposed, while in its crib or carriage, which combines the features of freedom of movement for the limbs of the infant with adequate covering, and which further includes, as features thereof, accessibility for redressing the infant.

To attain these objects and such further objects as may appear herein or be hereinafter pointed out, I make reference to the accompanying drawings, forming a part hereof, in which—

Figure 1 is a front plan view of my device;

Figure 2 is a back view of the same;

Figure 3 is a perspective view of my device, worn by the infant and applied in connection with a crib;

Figure 4 is a perspective view showing another position of my device;

Figure 5 is a perspective view of my device as worn by an infant, in the form of a robe;

Figure 6 is a back view of the same.

My device, in its general applicability, contemplates an improvement over the construction referred to in the patent to Painter No. 1,079,798, November 25, 1913.

My device comprises a jacket portion 10, the length of which is arranged to cover an infant to approximately its waist, and is made from blanket fabric. The jacket comprises a front 11, a back 12, formed with sections for defining the sleeves 13, near the ends whereof there are located draw-strings or ties 13a, to gather the sleeves near the ends snugly around the wrists of the infant.

The back 12 terminates adjacent the skirt por-

tion 14 at a distance calculated to be approximately near the small of the back of the infant.

The front portion 11 terminates into an extended section 15, having laterally directed flaps 16. To each side of the sections 16 there may be affixed the flaps 17. The section 15, flaps 16 and the flaps 17 define an area which is calculated to cover the width of the crib and extend beyond the same for three sides, to give a substantial tuck-in 18 at the sides and foot of the crib, as will more clearly appear in Figures 3 and 4.

The jacket is provided with a neck opening 19 and at the front thereof is formed with a slotted portion or opening 20, extending from the neck opening 19, throughout the entire length of the front 11 and into the section 15. The length of this opening is calculated to be substantially equivalent to the body of an infant, to and including its legs, for purposes which will appear more clearly as this description proceeds.

The edges 21 and 22 of the slit may be joined by suitable fastening means. It is preferred by me to provide the edges 21 and 22 with slide fastener elements, mounted upon stiffeners, to the edges 21 and 22, and including therewith an operating slider 23. To one of the edges there is affixed a flap 24. This is of sufficient width to act as a protective covering for the complementary fastener elements attached to the edges 21 and 22, thereby to protect the infant from direct contact with the metallic elements constituting the slide fastener.

With a construction as provided, to dress the infant, the slotted portion 20 is opened for its full length. The infant may then be inserted through the slit and the jacket disposed in position over the arms and chest of the infant. With this accomplished, the flaps 16 may be enveloped around the legs and back of the infant, to provide more or less of a robe, such as illustrated in Figure 5.

Where it is desired to use the garment for sleeping purposes, either for covering the infant in the crib or carriage, the extensions 16 and flaps 17 are spread out and the excess material covered over the mattress 25, tucking the flaps 17 underneath the mattress at the sides and foot thereof, to form the tuck-in portions 18, previously mentioned.

It will be observed that in this position, the jacket 10 forms an effective covering for the chest and back of the infant, leaving the arms free. The extensions 16 and 17 cover the lower half of the infant, as a blanket would, giving the limbs beneath the blanket perfect freedom. The

skirt portion 14 extends sufficiently below the edges 14a of the extensions 16 to provide adequate protection at the waist line.

It will be further observed that the skirt portion 14 terminates at such portion of the back of the infant that its undergarments below the waist line will not come in contact with the jacket. With the infant lying on its back, the usual protective covering, pads, rubber sheeting may 10 be applied in position.

The slitted portion 20, extending to the point 20a, located to correspond to the length of the infant, permits the slit 20 to be opened to reach the infant, to change its under garments. This 15 position is particularly illustrated in Figure 4. Thus while the infant is in its crib or carriage, should the occasion arise to change the infant's diapers, it is merely necessary to slide the operating member 23 to its lowermost point 20a, giving 20 full access to the infant.

In all other respects, the garment in accordance with my invention offers full protection or covering for the infant. The limbs have freedom below the waistline as well as above the waistline. 25 A sitting posture may readily be assumed with freedom, while offering security from exposure or falling from the crib or carriage.

The infant may be dressed, as already described, without the need for removing the infant 30 from the jacket or the infant may be lifted bodily, with its covering, wrapping the flaps or extensions 16 and 17 about the legs of the infant, securely protecting the entire infant and acting as an extended robe.

35 It will be understood that the flaps 17 may be an extension of the sections 16. Preferably, however, the portions 17 are separately connected by

a seam line 17a. This seam line is calculated to conform to the corner 17b of the mattress and enhances the neatness of arrangement of the lower half of the garment in its tucked-in position about the mattress.

5 In general it will be observed that I have provided a highly efficient infant's garment, robe and blanket or protective covering for infants, which provides security of coverage while giving the infant full freedom of movement.

10 Having thus described my invention and illustrated its use, what I claim as new and desire to secure by Letters Patent is—

An infant's combination garment, having a jacket portion and bed cover integral therewith, 15 the jacket portion having a back and front sewed to each other and a pair of sleeves integral with said front and back, the bed cover being an oblong sheet of the same material as the jacket and integral along the median portion of its upper 20 edge with the lower edge of the front, said garment having a longitudinal opening extending downwardly from the neck opening of the garment the length of the jacket and into the bed cover portion for a length approximating the 25 length of the body of the infant, and a closure for the opening, so that when the opening is closed the garment is employed as a robe and bed cover to retain the infant in position on the bed, the infant being covered from head to foot, 30 and when the opening is open the infant is retained in position by the back and sleeves, the body of the infant being disposed over the cover portion thus permitting the infant substantial freedom of movement and exposure.
